UNITED STATES PATENT OFFICE

LEONARD R. CROW, OF TERRE HAUTE, INDIANA

SUPPORTING DEVICE FOR ELECTRICAL APPARATUS

Application filed May 4, 1928, Serial No. 275,244. Renewed May 18, 1931.

My invention relates to improvements in supporting device for electrical apparatus, and it consists in the combinations, constructions, and arrangements herein described 5 and claimed.

An object of my invention is to provide a supporting device for electrical apparatus by means of which various electrical apparatuses, including electromagnets, may be supported in various positions for producing numerous electrical experiments.

A further object of my invention is to provide a device of the type described in which the same supporting means may be used in 15 various ways for accomplishing various experimental results.

A further object of my invention is to provide a device of the type described which is simple in construction, which may be 20 readily assembled, and which is durable and efficient for the purpose intended.

A further object of my invention is to provide a device of the type described which has novel means for completing circuits for 25 electrically connecting the electromagnets with a source of current irrespective of the positions in which the electromagnets are placed.

Other objects and advantages will appear 30 in the following specification, and the novel features of the invention will be particularly pointed out in the appended claims.

My invention is illustrated in the accompanying drawings, forming part of this application, in which

Figure 1 is a front elevation of my device illustrating the members thereof in one position and having a portion thereof broken 40 away,

Figure 2 is an enlarged section substantially along the line 2-2 of Figure 1,

Figure 3 is a front elevation of my device illustrating the members in a different position,

Figure 4 is a top plan view of a portion of my device,

Figure 5 is a front elevation of my device 50 showing the members in still another position,

Figure 6 is an end elevation of my device assembled as shown in Figure 5, and

Figure 7 is a top plan view of my device.

In carrying out my invention, I provide a base 1 having upright plugs 2 removably disposed in openings 3 and arranged to receive one end of lower supports 4 and 5. The lower support 4 is provided with an elongated slot 6 together with openings 7 and 8. The lower support 5 is provided with openings 9 and 10 which are in alignment with the openings 7 and 8, respectively. The lower support 5 is also provided with an opening 11 which is in substantial alignment with the slot 6. The lower supports 4 and 5 are provided with connecting plugs 12 which are rigidly secured thereto by any suitable means, such as pins 13. Upper or extension supports 14 and 15 have their lower ends disposed in engagement with the plugs 12 and in this manner are removably secured to the lower supports 4 and 5. The upper supports 14 and 15 are provided with aligned openings 16 and 17, respectively.

Top-engaging plugs 18 are disposed in the upper ends of the extensions 14 and 15 and are arranged to be received in openings 19 in a horizontal top 20. Referring to Figure 7, it will be noted that the top 20 is provided with an elongated guide slot 21 for a purpose hereinafter described. The top 20 is provided with four pairs of sockets numbering 22 and 23, 24 and 25, 26 and 27, and 28 and 29. These sockets extend through the top 20 and have their openings positioned adjacent the under surface 30 of the top. A conductor 31 is embedded in a groove 32 and has its ends secured to the sockets 22 and 24; a conductor 33 is embedded in a groove 34 and has its ends secured to the sockets 23 and 25; a conductor 35 is embedded in a groove 36 and has its ends secured to the sockets 26 and 28, and a conductor 37 is embedded in a groove 38 and has its ends secured to the sockets 27 and 29.

The base 1 is provided with three pairs of sockets numbering 39 and 40, 41 and 42, and 43 and 44. Knife switches 45 and 46 are disposed at each end of the base 1 as

shown in Figure 7. Terminal posts 47 and 48 of the switch 45, and terminal posts 49 and 50 of the switch 46 are electrically connected to the sockets 39 and 40, respectively. 5 The terminal post 51 of the switch 45 is electrically connected to the socket 41 and the terminal post 52 of the same switch is electrically connected to the socket 42. The terminal post 53 is electrically connected to 10 the socket 43, and the terminal post 54 is electrically connected to the socket 44.

I have provided two cable-supporting and actuating members 55 and 56 which are identical in construction, and a description 15 of one will apply to both. For a matter of description, we will select the cable-holding and actuating member 55 which is provided with a frame consisting of parallel spaced-apart wall members 57 and 58 having tongue portions 59 arranged to be received in the elongated slot 21 of the top member 20. A shaft or drum 60 is disposed between the walls 57 and 58 and operatively connected to a hand knob or wheel 25 61. Between the hand knob 61 and the wall 58, a ratchet wheel 62 is disposed and is rigid with the knob. A pawl 63 is pivotally mounted upon the wall 58 and is arranged to engage with the teeth of the ratchet wheel 62. A tape or cable 64 has one end rigidly secured to the drum 60 and the other end secured to an eyelet screw 65. I have numbered the corresponding parts of the 30 cable-supporting and actuating member 56 35 with numbers 57', 58', 59', 60', 61', 62', 63', 64' and 65' for the purpose of distinction, these numbers relating to the like members of the cable-supporting and actuating member 55.

40 I have shown additional supporting members such as relatively long supporting bars 66 and 67 which have their ends threaded so as to receive wing nuts 68 or the like. Relatively short threaded supporting bars 45 69 and 70 are also provided and arranged to receive the wing nuts 68. Gripping rings 71 and 72 are provided with internally threaded integral posts 73 and 74, respectively, which are arranged to receive 50 the eyelet screws 65 and 65'.

From the foregoing description of the various parts of the device, the operation thereof may be readily understood. My invention may be used in numerous ways to produce numerous electrical experiments. 55 One way in which my device may be used is illustrated in Figure 1 in which the relatively long supporting bars 66 and 67 are connected at their inner ends by means of a 60 thumb nut 75. A pendulum 76 having a U-shaped portion 77 is pivotally mounted upon the supporting bars 66 and 67. A disc 78 is removably secured to the pendulum 76 by any suitable means, such as a bolt 79. 65 The disc 78 may be of any desired material.

Electromagnets 80 and 81 are disposed in the gripping rings 71 and 72 and are held at spaced-apart positions by the relatively short supporting bars 69 and 70 owing to the fact that the outer ends of the electromagnets are secured to the inner ends of the relatively short supporting bars. The height of the inner ends of the electromagnets 80 and 81 may be adjusted by rotating the drums 60 and 60' by rotating the hand knobs 61 and 61'. The electromagnets are held in their adjusted positions by the pawls 63 and 63' which engage with the ratchet wheels 62 and 62'. Relatively short sets of cords 82 and 83 may be electrically connected to the electromagnets 80 and 81, respectively, and to the sockets 41, 42 and 43, 44, respectively. By connecting the sockets 39 and 40 with a circuit of a source of current, the switches 45 and 46 may be closed, thus allowing the source of current to pass through either the electromagnet 80 or the electromagnet 81, or both. Different effects may be had upon the pendulum as it is 50 swung between the electromagnets. 90

In Figure 3, I have shown the device assembled for another form of experiment. In Figure 3, I have secured the gripping rings 71 and 72 to the relatively short supporting bars 69 and 70. The electromagnets 80 and 81 are disposed in the gripping rings 71 and 72 and are thus held against lateral displacement. The eyelet screws 65 and 65' are disposed in the upper ends of the electromagnets 80 and 81, respectively, and the electromagnets are thus supported by the cables 64 and 64'. A motor 84 is disposed upon the base 1 and is provided with a disc such as that shown at 78 which is secured to a shaft 85 by means of the thumb nut 75. The disc 78 is arranged to be rotated. The relatively short sets of cords 82 and 83 have their upper plugs disposed in the sockets 28, 29 and 24, 25, respectively. The lower plugs of the sets of cords 82 and 83 are electrically connected to the electromagnets 80 and 81, respectively. 100 110

Relatively long sets of cords 86 and 87 extend from the sockets 41, 42 and 43, 44, respectively, to the sockets 26, 27 and the sockets 22, 23, respectively. Assuming that the sockets 39 and 40 are in electrical connection with a source of current, by closing either or both the switches 45 and 46, the source of current may pass through the electromagnets 80 and 81. The positions of the electromagnets 80 and 81 with respect to the disc 78 of the motor 84 have various effects upon the disc. 115 125

In Figures 5 and 6, I have shown another position in which my device may be disposed for creating another experiment. In this form, the relatively short supporting bars 69 and 70 are extended through the openings 7 and 9, respectively, of the lower 130

supports 4 and 5, respectively. The lower supports 4 and 5 may be rotated so as to allow the supporting bars 69 and 70 to extend outwardly instead of inwardly as shown in Figures 1 and 3. The gripping rings 71 and 72 are disposed upon the outer ends of the supporting bars 69 and 70. The cables 64 and 64' are passed through the gripping rings and secured to the ends of a core 88. The ordinary cores of the electromagnets 80 and 81 are removed and the electromagnets are disposed concentrically with the core 88. The relatively short sets of cords 82 and 83 extend from the sockets 41, 42 and 43, 44 to the sockets in the electromagnets 80 and 81, respectively.

The illustrations disclosed in Figures 1, 3, 5 and 6 are merely three ways in which my device may be used. There are, however, numerous other ways in which my device may be used.

I claim:

1. A device of the type described comprising a base, lower supports, means for securing one of the ends of said lower supports to said base, upper supports, means for securing said upper supports to the other ends of said lower supports, a top, means for securing said upper supports to said top, said supports having openings therein, relatively long supporting bars extending through openings in the upper supports, a thumb nut for connecting the inner ends of said relatively long supporting bars, and a pendulumlike member, said relatively long supporting bars being adapted to pivotally support said pendulumlike member.

2. A device of the type described comprising a base, lower supports, means for securing one of the ends of said lower supports to said base, upper supports, means for securing said upper supports to the other ends of said lower supports, a top, means for securing said upper supports to said top, said supports having openings therein, relatively long supporting bars extending through openings in the upper supports, a thumb nut for connecting the inner ends of said relatively long supporting bars, a pendulumlike member, said relatively long supporting bars being adapted to pivotally support said pendulumlike member, electromagnets and relatively short supporting bars extending through openings in said lower supports each of said short supporting bars being adapted to have one of said electromagnets secured to its inner end.

3. A device of the type described comprising a base, lower supports, means for securing one of the ends of said lower supports to said base, upper supports, means for securing said upper supports to the other ends of said lower supports, a top, means for securing said upper supports to said top, said

supports having openings therein, relatively long supporting bars extending through openings in the upper supports, a thumb nut for connecting the inner ends of said relatively long supporting bars, said relatively long supporting bars being adapted to pivotally support a pendulum having a metallic disc secured to the lower end thereof, relatively short supporting bars extending through openings in said lower supports each of said short supporting bars being adapted to have an electromagnet secured to its inner end, and means cooperating with said relatively short supporting bars for adjustably supporting said electromagnets.

4. A device of the type described comprising a base, lower supports, means for securing one of the ends of said lower supports to said base, upper supports, means for securing said upper supports to the other ends of said lower supports, a top, means for securing said upper supports to said top, said supports having openings therein, relatively long supporting bars extending through openings in the upper supports, a thumb nut for connecting the inner ends of said relatively long supporting bars, said relatively long supporting bars being adapted to pivotally support a pendulum having a metallic disc secured to the lower end thereof, relatively short supporting bars extending through openings in said lower supports each of said short supporting bars being adapted to have an electromagnet secured to its inner end, means cooperating with said relatively short supporting bars for adjustably supporting said electromagnets, said means comprising gripping rings adapted to be disposed concentric with said electromagnets, supporting cables, each having one of its ends secured to said gripping rings, and means for receiving the other ends of said cables and for varying the length thereof.

5. A device of the type described comprising a base, supports, a top having an elongated opening therethrough, said supports being disposed between said top and said base for supporting said top, cable-supporting and actuating members disposed upon said top in engagement with said elongated opening, cables carried by said cable-supporting and actuating members for supporting electromagnets having sockets therein, said base having main sockets adapted to be electrically connected to a source of current, auxiliary sockets, a switch, and means for electrically connecting said auxiliary sockets with said main sockets when said switch is turned on.

6. A device of the type described comprising a base, supports, a top having an elongated opening therethrough, said supports being disposed between said top and said base for supporting said top, cable-sup-

- porting and actuating members disposed upon said top in engagement with said elongated opening, cables carried by said cable-supporting and actuating members for supporting electromagnets having sockets therein, said base having main sockets adapted to be electrically connected to a source of current, auxiliary sockets, a switch, means for electrically connecting said auxiliary sockets with said main sockets when said switch is turned on, end sockets disposed in said top, center sockets disposed in said top, means for electrically connecting said end sockets with their respective center sockets, a relatively short set of conductor cords each cord having a plug upon each end, each plug being adapted to be disposed in a socket of a desired set of said sockets, and a relatively long set of conductor cords having plugs upon the ends thereof each of said plugs being adapted to be disposed in a socket of other sets of said sockets.
7. A device of the type described comprising a base, a top having an elongated opening therein, cable-supporting and actuating members disposed upon said top and in registration with said opening, supports disposed between said base and said top and secured in place, each of said supports being adapted to be rotated with respect to said base and said top and having openings therethrough, relatively short supporting bars extending through the openings in said supports, a gripping ring secured to the outer end of each of said supporting bars, cables each having its upper end carried by one of said cable-supporting and actuating members and its other end extending through one of said gripping rings and secured to a relatively long core having electromagnets movably disposed thereupon and each provided with sockets, main sockets disposed in said base, two sets of auxiliary sockets disposed in said base, a switch for each of said sets of auxiliary sockets adapted to electrically connect said auxiliary sockets with said main sockets, said main sockets being adapted to be electrically connected to a source of current, and relatively short sets of conductor cords each cord provided with a plug adapted to be disposed in a socket formed of each of said sets of auxiliary sockets and a socket in each of said electromagnets.
8. A device of the type described comprising a base, supporting members provided with openings carried by said base, a top having a relatively long opening therethrough disposed upon said supporting members, relatively long supporting bars, relatively short supporting bars, said supports having openings therethrough, electrical experimenting devices, said supporting bars being adapted to be secured to said supports at the openings therein for supporting said electrical experimenting de-

vices, cable-supporting and actuating members disposed upon said top adjacent the relatively long opening therein, cables each having its upper end secured to one of said cable-supporting and actuating members, 70 and means carried by the other end of each of said cables for securing each one of said cables to one of said electrical experimenting devices.

Signed at Terre Haute in the county of 75 Vigo and State of Indiana this 1st day of May A. D. 1928.
